F. O. CONILL

RAZOR CONSTRUCTION

Filed Jan. 10, 1923

12d 22d 20^a Fernan O. Conill
By his Attorney Robert S. Blair

UNITED STATES PATENT OFFICE.

FERNAN O. CONILL, OF MARSEILLE, FRANCE.

RAZOR CONSTRUCTION.

Application filed January 10, 1923. Serial No. 611,694.

To all whom it may concern:

Be it known that I, FERNAN O. CONILL, a citizen of the Republic of Cuba, and a resident of Marseille, France, have invented an improvement in a Razor Construction, of which the following is a specification.

This invention relates to razor construction. One of the objects thereof is to provide a simple and practical razor construction having certain of the characteristics and advantages of the usual type of so-called straight razor but having a highly efficient and more effective cutting action than the ordinary type of straight razor. Another object is to provide a razor construction of the above general type in which the normal or usual cutting action of the blade due to a movement of translation or due to the drawing thereof manually in the usual manner is effectively supplemented by or combined with the cutting action resulting from a movement of the blade in a direction substantially coincident with that of its cutting action. Moreover, this invention aims to provide in a razor construction of the above type rugged and durable mechanism for supplementing the normal cutting action of the blade and which mechanism will be of light weight and compactness of arrangement so that convenience as well as precision of manipulation and flexibility of control may not be impaired. Other objects will be in part obvious or in part pointed out hereinafter.

The invention accordingly consists in the features of construction, combinations of elements and arrangements of parts as will be exemplified in the structure to be hereinafter set forth and the scope of the application of which will be indicated in the following claims.

In the accompanying drawings, in which are shown several of various possible embodiments of this invention and in which similar reference characters refer to similar parts throughout the several views,

Figure 1 is a plan view, and

Figure 2 is a side view, partly in section, of one form of razor construction shown

in extended or opened relation, certain parts being omitted to show the construction more clearly;

Figure 3 shows a detached plan view and a side view of a blade-operating member forming part of the construction shown in Fig. 1;

Figure 4 is a plan view of a guard plate, and

Figure 5 is an enlarged, detailed, sectional view of the apparatus in assembled relation, the section being taken substantially on the line 5—5 of Fig. 1, and showing the details of the blade-reciprocating mechanism;

Figure 6 is a plan view of a modified form of blade construction, and

Figure 7 is a side view thereof as viewed from the left in Fig. 6;

Figure 8 is a sectional view taken on the line 8—8 of Fig. 6;

Figure 9 is a sectional view showing a modified form of blade-operating mechanism; and

Figure 10 is an enlarged sectional view taken on the line 10—10 of Fig. 9.

Referring now to the drawings and more particularly to Figs. 1 and 2, there is shown a razor handle member generally indicated at 10 and having preferably the form of the usual straight razor handle, it being noted that it may conveniently comprise two spaced members 10^a and 10^b suitably secured together in spaced relation and adapted to receive the blade therebetween when the razor is closed substantially upon itself. At one end of the handle member 10 and pivoted thereto as at 11 is a blade-supporting member, generally indicated at 12 and comprising preferably a main body portion 12^a at one end thereof, through which the pivoting member 11 of the handle member 10

preferably extends, and the guiding portion 12^b at the other end thereof. The main body portion 12^a preferably takes a form substantially similar to the tang or shank usually employed in straight razor construction in order that the manipulation and control of the device herein described may be brought about with the same convenience in

so far as the gripping of the razor manually is concerned, as is the case with the ordinary straight razor. Thus also, for example, the main body portion 12^a may be roughened or 5 serrated as at 12^b to insure a positive gripping of the device.

The guiding portion 12^b of the blade-mounting member 12 is preferably of somewhat greater lateral expanse, as is clearly 10 shown in Fig. 1, than the main body portion 12^a and preferably takes the form of a plate-like member provided with projecting parallel side walls 13 and 14 adapted to 15 form suitable guiding ways for a blade-carrying member 15 fitting snugly between the parallel guiding walls 13 and 14. The blade-supporting member 15 is preferably of less longitudinal extent than the portion 12^b of the blade-mounting member 12 in order 20 that the blade-supporting member 15 may partake of an appreciable sliding movement within the guiding portion 12^b, being guided during such sliding movement by the oppositely spaced walls 13 and 14.

25 Referring to Fig. 3, it will be seen that the blade-supporting member 15 is provided with two projecting bosses 15^a and 15^b spaced from each other in the direction of the 30 length of the member 15 and preferably rounded upon their respective outer ends. Moreover, openings 15^c and 15^d extend through the member 15 and also through the bosses 15^a and 15^b, respectively.

The blade-supporting member 15 when 35 slidably positioned in the guiding portion 12^b of the blade-mounting member 12 has its projecting bosses 15^a and 15^b projecting outwardly beyond the plane of the outer edges of the oppositely disposed guiding walls 13 40 and 14, and when so related with respect to the guiding portion 12^b a blade member 16 preferably double-edged and thus having the two cutting edges 16^a and 16^b is placed upon the blade-supporting member 15 with 45 the bosses 15^a and 15^b extending through the centrally positioned and longitudinally extending slot or opening 16^c in the blade member 16. The slot 16^c is preferably of such longitudinal extent that it will snugly 50 receive the projecting bosses 15^a and 15^b thereby to align the blade member 16 with respect to the blade-supporting member 15 and to prevent a relative displacement therebetween.

55 Superimposed upon the blade member 16 is a guard plate 17 (see Figs. 4 and 5) having openings 17^a and 17^b formed and spaced substantially similarly as are the projecting bosses 15^a and 15^b so that when the 60 guard member 17 is superimposed upon the blade member 16 the bosses 15^a and 15^b will project, respectively, through the openings 17^a and 17^b. The guard member 17 is comb-shaped at its opposite edges, as is generally 65 indicated at 17^c and 17^d, respectively, and it

will be seen that when the guard member 17 is superimposed upon the blade member 16 the comb-shaped side edges 17^c and 17^d will be aligned with and will coat with the cutting edges 16^a and 16^b of the blade member 16, respectively, the projecting bosses 15^a and 15^b of the blade-supporting member 15 insuring the maintenance of these several parts in proper alignment.

In order to maintain the several parts 70 above mentioned in the assembled relation as above described, the guiding portion 12^b is slotted at two spaced points, as at 12^c and 12^d, the slots 12^c and 12^d extending longitudinally of the member 12^b (see Figs. 2 and 80 5). Extending through the slots 12^c and 12^d in the guiding portion 12^b and passing through the openings 15^c and 15^d in the bosses 15^a and 15^b in the blade-supporting member 15 are the bolts 18 and 19 respectively. The bolts 18 and 19 are provided with shoulders 18^a and 19^a, respectively, adapted to abut against the under side of the blade-supporting member 15 in order that the thumb-nuts 18^b and 19^b may securely 90 clamp the member 15, the blade 16 and the guard member 17 together as above described and as more clearly shown in Fig. 5. The shoulders 18^a and 19^a, moreover, are of such extent in an axial direction as to avoid 95 clamping the guiding portion 12^b to the blade-supporting member 15 and to permit freedom of relative movement in a longitudinal direction therebetween, the headed 100 portions of the bolts 18 and 19 acting to prevent the blade-supporting member 15 with its associated parts from separating from the guiding portion 12^b of the blade-mounting member 12.

105 Turning now to Fig. 3, it will be noted that the blade-supporting member 15 is provided with an extension 15^e carrying in its extreme end the transversely extending slot 15^f. Referring now to Figs. 1, 2 and 5, it will be noted that at an intermediate point 110 in the main body portion 12^a of the member 12 the former is enlarged transversely of itself as at 12^e. This enlargement 12^e may conveniently be bored out in a direction transversely to the plane of the member 12 and it is preferably threaded interiorly as 115 at 12^d (see Fig. 5). Into this threaded opening 12^d in the enlargement 12^e is threaded a sleeve member 20 preferably closed at its lower end, as at 20^a, and upon the upwardly 120 projecting threaded portion of the sleeve 20 as viewed in Fig. 5 is threaded another sleeve member 21 adapted to coat with the sleeve member 20 to rotatably support therein a rotatable member taking the form of a short shaft 22 provided at its inner end with a crank disc 22^a, the latter being housed within the sleeve 20 and carrying also an eccentrically positioned crank pin 22^b. The sleeve 20 is cut away as at 20^b to permit the 125 130

extension 15^e to extend therethrough and into the sleeve member 20, the crank pin 22^b engaging within the transversely extending slot 15^f in the extension 15^e. At the upper 5 end of the shaft 22 the latter is suitably formed as at 22^c for detachable engagement with the end driving member of a flexible shaft, diagrammatically indicated at 23.

The flexible shaft 23 may be driven from 10 any suitable source (not shown in the drawings) at a suitable rate of speed and when so driven will rotate the crank disc 22^a which, through the crank pin 22^b and the connection of the latter with the blade- 15 mounting member 15, will cause the latter together with the blade and guard member 17 to be reciprocated with respect to the guiding portion 12^e of the main blade- mounting member 12. Thus, when the parts 20 are assembled as above described and the razor opened up and grasped by the hand in the usual manner to give the cutting edge of the blade 16 a movement of translation, the reciprocation of the blade member 16 as 25 above described causes the cutting action of the blade due to the movement of translation to be supplemented by the cutting action of the blade resulting from the reciprocation in a direction substantially coincident 30 with that of the cutting edge of the blade itself.

Turning now again to Fig. 1, it will be seen that the handle member 12 is cut away as at 10^e, 10^d and 10^e to accommodate the 35 sleeve member 21 and the thumb-nuts 19^b and 18^b, respectively, when the parts are folded together or upon one another in effect to sheath the cutting blade between the two members 10^a and 10^b of the handle member 10.

Turning now to Figs. 6 and 7, there is shown a modified form of construction in which certain of the features hereinbefore described are attained in a somewhat more 45 simplified mechanical arrangement. The blade-mounting member 12 is provided with a guiding portion 12^e (see more particularly Fig. 8) having formed on its under side a dove-tailed guiding way 12^f within which is 50 received a substantially similarly formed guiding member 24^a preferably integrally formed with the blade member 24 in order to permit the latter to be slidably guided with respect to the member 12^e. As will be 55 seen from Fig. 8, the parts are preferably so proportioned and shaped as to assume in the aggregate a form substantially similar to the blade of the usual straight razor.

Upon the upper side of the guiding portion 12^e is mounted a guard plate 25 preferably substantially comb-shaped, as indicated in dotted lines at 25^a in Fig. 6, adapted to coact with the cutting blade 24. The guiding portion 12^e of the blade-mounting member 12 has mounted upon it two bosses 26

and 27 spaced from one another and adapted to form with suitably formed projecting portions 25^b of the guard plate 25 hinges for permitting the guard plate 25 to be swung into operative position (as shown in 70 dotted lines in Fig. 6), or into inoperative position (as shown in full lines in Fig. 6).

At a substantially central point in the guide plate 25 and adjacent the guiding portion 12^e there is formed an opening 25^c 75 through which is adapted to extend a substantially U-shaped spring 28 rigidly secured to the guiding portion 12^e and adapted to coact with the portion 25^d of the guard plate 25, which portion is preferably bent 80 so as to extend substantially transversely of the plane of the guard plate 25 itself. This relation is more clearly shown in Fig. 8. With this construction the U-shaped spring 28 acts to securely hold the guard plate 25 85 in either position into which it may be placed. Thus, in Fig. 8 the guard plate 25 is shown in dotted lines in operative relation with respect to the plate member 24 and is shown in full lines as swung away 90 from the blade 24. The U-shaped spring 28 coacts with the transversely bent portion 25^e of the plate 25 to hold the plate 25 in either of these positions, and reference to Fig. 8 shows that in the latter position the guard plate 25 is securely held when swung away 95 from the blade 24 in substantially the same plane as the plane of the blade 24 itself, thus permitting the usual stropping of the razor blade to be carried on without interference 100 by the guard plate 25. Moreover, also, the cleaning of the parts may thus be readily carried on after use. Reference to Fig. 8 will also show that the guard plate 25 is provided with suitable projections 25^f which 105 may, for example, be formed by stamping in order to hold the comb-shaped edge of the guard plate 25 at a suitable distance from the cutting edge of the blade.

As is shown in Figs. 6 and 7, the guiding portion 12^e may conveniently be made separate from the main body portion 12^a of the blade-mounting member 12 and may conveniently be secured thereto as by the cap screws 12^g in order to permit ready assembly 110 of the parts and also to permit replacement or disassembly of the parts.

The blade member 24 is provided with an extension, preferably integrally formed therewith and indicated at 24^b, the extension 24^b being substantially similar to the extension 15^e of the blade-supporting member 15 hereinbefore described and shown more particularly in Figs. 1, 3 and 5, and, being provided with a transversely extending slot 24^c, is adapted to be mechanically connected to the crank pin 20^a operated by the rotary shaft 22 (see Fig. 5) in substantially the same manner as already hereinbefore described and more particularly shown 125 130

in Fig. 5. In Figs. 6 and 7, however, the main body portion 12^a of the blade-mounting member 12 is not shown in detail as to these features of construction, reference being had particularly to Fig. 5 for these details of construction.

In operation the shaft 22 is operated at a suitable rate of speed, and through the crank pin connection with the extension 24^b 10 a reciprocation of the blade member 24 with respect to the guiding member 12^a is brought about, thus, supplementing the normal cutting action of the blade due to a movement of translation (it being understood 15 that the blade-mounting member 12 is associated with the usual handle construction, as shown, for example, in Figs. 1 and 2) by the cutting action of the blade due to its movement in a direction substantially coincident with that of the cutting edge of the blade itself.

In Figs. 9 and 10 I have shown a more convenient form of mechanical operating mechanism for reciprocating the cutting 25 blades hereinbefore described; and referring more particularly to Fig. 10, there is shown a blade-mounting member, generally indicated at 12, pivotally connected to the handle member 10 as at 11^a, the pivoting pin

30 11^a being, however, offset with respect to the member 12 in substantially the manner shown in Fig. 9. The main body portion 12^a of the blade-mounting member 12 is bored out throughout substantially its entire 35 extent, as at 29, in order to form a housing as well as a bearing for an operative shaft 30, one end of which is suitably formed as at 30^a for detachable engagement with the end driving member 31 of a flexible shaft 40 indicated at 32, a sleeve 32^a being threaded upon the extreme end of the main body portion 12^a to maintain the detachable connection of the shaft 30 with the flexible shaft 32.

45 At the other end of the shaft 30 there is rigidly mounted a cylindrical cam 33, shown more clearly on enlarged scale in Fig. 10, provided with a cam groove 33^a. At this end of the main body portion 12^a of the 50 blade-mounting member 12 the former is suitably formed to provide a cylindrical housing 12^b adapted to surround the cylindrical cam 33 and provided at its forward end with an opening 12^k through which the 55 extension, generally indicated at 34, may pass for operative engagement with the cam member 33. At this point it may be noted that the extension 34 is connected to the blade member in any suitable manner as, for example, as hereinabove described, and it may conveniently take the form of the extension 15^e (see Figs. 1 and 3) in so far as its connection with the blade member 60 15 is concerned, or it may be integrally formed with the blade, as is the extension

24^b of the blade 24 (see Fig. 6). It may also be noted that the extension 34 may be guided for relative slidable movement with respect to the guiding portion 12^b as hereinabove described.

70 At its inner or extreme end the extension 34 has rotatably mounted upon it a roller 35, as by the pin 36, the roller 35 being suitably proportioned to engage and operate within the cam groove 33^a of the cam member 33. As the shaft 30 is rotated through the flexible shaft connection 32 the cylindrical cam 33 is likewise rotated, and through the cam groove 33^a and the pin and roller connection 35 with the extension 34 the reciprocation of the blade is brought about.

75 In connection with the mechanical operating mechanisms shown in Figs. 9 and 10, it might be noted that the mechanism is exceedingly compact and is substantially entirely encased or housed within the main body portion 12^a of the blade-mounting member 12; and it may also be noted that the operative connection to the flexible shaft is made at a point, namely, in the extreme 80 end of the blade-mounting member 12, where it is least apt to interfere with or encumber the precise manual manipulation of the razor structure as a whole.

85 It will thus be seen that there has been provided in this invention a razor construction in which the several objects hereinbefore set forth, as well as many advantages, are achieved. It will be seen that the normal cutting action of the razor blade as manually guided is effectively combined with or supplemented by the cutting action due to the movement of the blade in a direction substantially coincident with that of its cutting edge and that such combined cutting action is attained without sacrificing compactness of construction, precision of manipulation, and flexibility of control. The construction is of light weight and is 90 not cumbersome and, moreover, it may be noted that the above advantages are attained without impairment of safety in operation and use of the razor.

95 As many possible embodiments may be made of this invention and as many changes 100 might be made in the embodiment herein set forth, it is to be understood that all matter hereinbefore set forth or shown in the accompanying drawings is to be interpreted as illustrative and not in a limiting 105 sense.

110 I claim as my invention:

1. In razor construction, in combination, a cutting blade, a handle member therefor adapted to form substantially a sheath for said blade, means mounting said blade with respect to said handle members adapted to permit said blade to be swung toward said handle to be substantially sheathed thereby or away from said handle thereby to per-

- 7 permit said blade to be given manually a movement of translation substantially transversely to the direction of the cutting edge of said blade, said blade mounting means
 5 including guiding means for said blade adapted to permit slidable movement of the blade with respect to said mounting means and in a direction substantially lengthwise of the cutting edge of said blade, and means
 10 associated with said blade-mounting means for giving said blade a substantially sustained reciprocating movement with respect to said mounting means and substantially in the direction of the cutting edge of said
 15 blade.
2. In razor construction, in combination, a cutting blade, a handle member therefor adapted to form substantially a sheath for said blade, means mounting said blade with respect to said handle member adapted to permit said blade to be swung toward said handle to be substantially sheathed thereby or away from said handle thereby to permit said blade to be given manually a movement 20 of translation substantially transversely to the direction of the cutting edge of said blade, means slidably supporting said blade upon said mounting means and adapted to permit said blade to slide with respect thereto and in a direction substantially lengthwise of the cutting edge of said blade, and mechanically actuated means mounted upon one end of said blade-mounting means for giving said blade a reciprocating movement 25 with respect thereto and substantially in the direction of the cutting edge of said blade.
3. In razor construction, in combination, a cutting blade, a handle member therefor adapted to form substantially a sheath for said blade, means mounting said blade with respect to said handle member adapted to permit said blade to be swung toward said handle to be substantially sheathed thereby or away from said handle thereby to permit said blade to be given manually a movement 30 of translation substantially transversely to the direction of the cutting edge of said blade, a guard member associated with said blade and adapted to limit the cutting action of said blade, means associated with said blade-mounting means for giving said blade a vibratory movement substantially in the direction of the cutting edge of said blade and means mounting said guard member with respect to said blade adapted to permit said guard member to be moved into operative position with respect to said blade or out of operative relation with respect thereto.
4. In razor construction, in combination, a cutting blade, a handle member therefor adapted to form substantially a sheath for said blade, means mounting said blade with respect to said handle member adapted to permit said blade to be swung toward said handle to be substantially sheathed thereby or away from said handle thereby to permit said blade to be given manually a movement of translation substantially transversely to the direction of the cutting edge of said blade, said blade mounting means including means for slidably supporting said blade to partake of a movement with respect to said mounting means in a direction substantially lengthwise of the cutting edge of the blade, a 70 rotatable member associated with said blade-mounting means, and a connection between said blade and said rotatable member adapted upon rotation of the latter to reciprocate said blade with respect to said mounting means and in substantially the direction of the cutting edge of said blade.
5. In razor construction, in combination, a cutting blade, a handle member therefor adapted to form substantially a sheath for said blade, means mounting said blade with respect to said handle member adapted to permit said blade to be swung toward said handle to be substantially sheathed thereby or away from said handle thereby to permit said blade to be given manually a movement 75 of translation substantially transversely to the direction of the cutting edge of said blade, means slidably supporting said blade on said mounting means and adapted to permit said blade to slide with respect thereto and in a direction substantially lengthwise of the cutting edge of said blade, a member rotatably supported upon said blade-mounting means and extending in substantial alignment therewith, and a connection between said blade and said rotatable member adapted upon rotation of the latter to reciprocate said blade with respect to said mounting means and in substantially the direction of the cutting edge of said blade.
6. In razor construction, in combination, a cutting blade, a handle member therefor, means mounting said blade upon said handle member adapted to permit said blade to be swung toward said handle or away from said handle thereby to permit said blade to be given manually a movement of translation substantially transversely to the direction of the cutting edge of said blade, said blade-mounting means comprising a guiding portion at one end thereof to permit said blade to slide relative thereto and a main body portion at the other end pivotally connected to said handle member, and a shaft rotatably mounted upon said main body portion of said blade-mounting means having at one end thereof a mechanical connection with said blade adapted upon rotation of said shaft to reciprocate said blade in said guiding portion with respect to said blade-mounting means and having at the other end means adapted to form a connection with a flexible shaft.
7. In razor construction, in combination,

- 1 a cutting blade, a handle member therefor, means mounting said blade upon said handle member adapted to permit said blade to be swung toward said handle or away from said handle thereby to permit said blade to be given manually a movement of translation substantially transversely to the direction of the cutting edge of said blade, said blade-mounting means comprising a 10 guiding portion at one end thereof to permit said blade to slide relative thereto and a main body portion at the other end pivotally connected to said handle member, said main body portion being bored out, and a shaft rotatably housed within said main body portion having at one end thereof a mechanical connection with said blade adapted upon rotation of said shaft to reciprocate said blade in said guiding portion with respect to said blade-mounting means and having means at the 15 other end for rotating said shaft.

2 8. In razor construction, in combination, a cutting blade, a handle member therefor, means mounting said blade with respect to said handle member adapted to permit said blade to be swung toward said handle into inoperative position or away from said handle into operative position thereby to permit said blade to be given manually a movement of translation substantially transversely to the direction of the cutting edge of said blade, a guard member associated with said blade adapted to coat therewith and to limit the cutting action thereof, and means mounting said guard member with respect to said blade adapted to permit said guard member to be swung into operative position with respect to said blade or out of operative relation with respect thereto.

3 9. In razor construction, in combination, a cutting blade, a handle member therefor, means mounting said blade with respect to said handle member adapted to permit said blade to be swung toward said handle into inoperative position or away from said handle into operative position thereby to permit said blade to be given manually a movement of translation substantially transversely to the direction of the cutting edge of said blade, a guard member associated with said blade adapted to coat therewith and to limit the cutting action thereof, and means mounting said guard member with respect to said blade adapted to permit said guard member to be swung away from said blade and substantially into the plane of said blade to permit stropping of said blade.

4 10. In razor construction, in combination, a cutting blade, a handle member therefor, means mounting said blade with respect to said handle member adapted to permit said blade to be swung toward said handle into inoperative position or away from said handle into operative position thereby to permit

5 11. In razor construction, in combination, a cutting blade, a handle member therefor, means mounting said blade with respect to said handle member adapted to permit said blade to be swung toward said handle into inoperative position or away from said handle into operative position thereby to permit said blade to be given manually a movement of translation substantially transversely to the direction of the cutting edge of said blade, a guard member associated with said blade adapted to coat therewith and to limit the cutting action thereof, means mounting said guard member with respect to said blade adapted to permit said guard member to be swung away from said blade, and means adapted to hold said guard member when swung away from said blade in substantially the same plane as said blade to permit stropping thereof.

6 12. In razor construction, in combination, a cutting blade, a handle member therefor, means mounting said blade with respect to said handle member adapted to permit said blade to be swung toward said handle into inoperative position or away from said handle into operative position thereby to permit said blade to be given manually a movement of translation substantially transversely to the direction of the cutting edge of said blade, a guard member associated with said blade adapted to coat therewith and to limit the cutting action thereof, means mounting said guard member with respect to said blade adapted to permit said guard member to be swung away from said blade and substantially into the plane of said blade to permit stropping of said blade, and spring means adapted to hold said guard member in either position into which it is swung.

7 13. In razor construction, in combination, a cutting blade, a handle member therefor, a blade-holding member comprising a guiding portion at one end thereof adapted to permit said blade to slide relative thereto and a main body portion at the other end thereof pivotally connected to said handle member thereby to permit said blade to be swung into inoperative position toward said handle or into operative position away from said handle to permit said blade to be manually given a movement of translation substantially transverse in its direction to that of the cutting edge of said blade, and a rotatable member mounted upon said main body portion of said blade-holding means having at one end thereof a mechanical connection with said blade adapted upon rotation of said rotatable member to reciprocate said blade in said guiding portion with respect to said blade-holding member and having connected at the other end thereof means for rotating said rotatable member, said mechanical connection with said blade being detachable to permit removal of said blade from said blade-holding means.

8 14. In razor construction, in combination, a cutting blade, a handle therefor adapted to form substantially a sheath for said blade, means mounting said blade with respect to said handle member adapted to permit said

blade to be swung toward said handle to be substantially sheathed thereby or away from said handle thereby to permit said blade to be given manually a movement of translation substantially transversely to the direction of the cutting edge of said blade, and means adapted to be operated from a source

of energy for vibrating said blade substantially in the direction of the cutting edge of said blade.

In testimony whereof, I have signed my name to this specification this 5th day of January, 1923.

FERNAN O. CONILL.
